AUTOMATIC CONTROL SYSTEM FOR ELECTRIC RAILWAYS.

1,082,956.

Specification of Letters Patent. Patented Dec. 30, 1913.

Application filed February 7, 1912. Serial No. 676,003.

To all whom it may concern:

Be it known that I, BENJAMIN F. HUTCHES, Jr., a citizen of the United States, residing at Allendale, county of Bergen, and State of New Jersey, have invented an Improved Automatic Control System for Electric Railways, of which the following is a specification.

This invention relates to a novel system for controlling electrically propelled cars and trains in such a manner that collisions are effectively prevented without the use of any signal or other additional wires.

The system is more particularly designed to protect single track railways having a plurality of switches although it may also be readily adapted to other purposes.

The system is such that if a car has arrived on a switch and there is no clear track ahead, the electric current is automatically cut off from the switch until said track has been cleared.

In the accompanying drawing: Figure 1 is a diagram showing my improved automatic control system applied to a track section having three switches; Fig. 2 is a diagram of one of the circuit changers; Fig. 3 a similar view thereof, showing the parts in a different position, and Fig. 4 a diagram showing the additional resistance contained in the cars.

The track is shown to comprise the single track sections 10, 11, 12, 13 which are connected by switches 14, 15, 16 respectively, the rails of all sections being conductively connected in suitable manner. The correspondingly arranged trolley wire or third rail comprises the single sections 17, 18, 19, 20 and the double or twin sections 21, 22, 23, the single sections being insulated from the double sections as at 24. The insulating points are arranged within the double wire sections in close proximity to their connecting points with the single wire sections, so that each single wire terminates in a fork as clearly illustrated in Fig. 1. At each of the switches there is arranged a circuit changer which controls the admission of electric current into the trolley wires of the corresponding switch and of the adjoining single track sections. The drawing shows three circuit changers A¹, A², A³ which are by branches 25, 26, 27 connected to a feed wire 28 while a suitable source of electricity 29 is by wires 30, 31 connected to track section 10 and feed wire 28 respectively.

Each circuit changer comprises essentially a pair of electromagnets 32, 33 and a pair of opposed electromagnets 34, 35 between the spaced cores of which is free to oscillate an armature 36 suspended at 37 in such a manner that if no current is flowing through the electromagnets, the armature occupies a central position. Electromagnets 32, 33 are adapted to influence an additional armature 38 forming part of a spring 39, the upper end of which is firmly clamped to a support 39^a, said spring withdrawing armature 38 from the cores of said electromagnets when the latter are deenergized. Electromagnet 32 is provided with a primary low resistance winding 40 one end of which is by wire or conductor 41 connected to a contact 42 while its other end is by wire 43 connected to the bifurcated end of the single trolley wire leading toward the right from the circuit changer (Fig. 2), say to wire 19. The primary winding 44 of electromagnet 33 is by wire 45 connected to a contact 46 and by wire 47 to the bifurcated end of the single trolley wire leading toward the left, say to wire 18. From the primary windings 48, 49 of electromagnets 34, 35 which are connected in parallel, a wire 50 leads to both trolley wires of the switch, say to wires 15, while a wire 51 connects said windings with a contact piece or bridge 52 mounted on armature 36 and insulated therefrom as at 53. In Fig. 1, wire 51 is shown to be led along armature 36, while in Figs. 2 and 3 wire 51 is illustrated as flexible, so as to be directly drawn toward bridge 52, thus avoiding the drawing from being obscured by showing insulation between armature 36 and wire 51. When armature 36 is swung toward the left (Fig. 2), it conductively connects the contacts 42, 46, while when it is swung toward the right (Fig. 3), it conductively connects a pair of contacts 54, 55. Of these, contact 54 is by wire or conductor 56 connected to wire 43 and contact 55 is by wire 57 connected to wire 47. All of the primary windings and wires or conductors above mentioned should be of such dimensions as to readily permit the passage of the electric current necessary for operating the cars or trains that pass the track section controlled by each circuit changer.

In addition to the primary windings, each of the electromagnets contains a secondary high resistance winding, electromagnet 32

being provided with a secondary winding 58, one end of which is connected to wire 43, while its other end is by wire 59 connected to a conductor 60 that connects armature 38 and spring 39 with armature 36. The secondary winding 61 is with one end connected to wire 47, while its other end is by wire 62 connected to conductor 60. The secondary windings 63, 64 of electromagnets 34, 35 are connected in series, the free end of winding 63 being connected to wire 50, while the free end of winding 64 is by wire 65 connected to a contact 66 adapted to be engaged by armature 38 when electromagnets 32, 33 are deenergized.

Before explaining the various circuits in detail, it may be stated in general elucidation of the device that when a car travels along a single track section of the line, current is supplied to the corresponding trolley wire section through the circuit changers arranged at the track switches that flank said single track section. So for instance if a car 67 travels along track section 12 in the direction of arrow *a* (Fig. 1), the armatures 36 of circuit changers A^2 A^3 are swung toward the left (by reasons herein-after more fully explained). Part of the current necessary for operating car 67 flows from feed wire 28 through branch 26, armature 36 of circuit changer A^2 , contact 42, wire 41, winding 40 of electromagnet 32 and wire 43 to trolley wire 19, while the other part of the current is supplied to wire 19 through branch 27, armature 36 of circuit changer A^3 , contact 46, wire 45, winding 44 of electromagnet 33, and wire 47, all of circuit changer A^3 . In order to maintain the armatures 36 in their proper positions, even if the controller 68 of the car is turned to cut off the motor current, an additional comparatively high resistance 69 is interpolated between the conductors 70, 71 leading from the controller to the wheels 45 and trolley respectively. In this way a small current will continuously flow through electromagnets 32, 33 of circuit changers A^2 A^3 respectively, as long as a car passes track section 12, so that the position of the armatures 36 is rendered independent of the position of the controller handle.

Fig. 1 further shows a car 72 passing switch 14 in the direction of arrow *b*. This car is free to proceed and meet car 67 in switch 15 and receives its operative current from the circuit changers of the switch 15 and of the switch located to the left of switch 14, the last named switch being not shown in the drawing. Part of the current for operating car 72 flows from branch 26 through the armature 36 of circuit changer A^2 , contact 46, wire 45, winding 44, wire 47, trolley wire 18, wire 43 of circuit changer A^1 , wire 56, contact 54, bridge 52 of the armature 36 of circuit changer A^1 which is

swung toward the right, wire 51, windings 48, 49 of electromagnets 34, 35 and wire 50. The remainder of the current is supplied from the circuit changer of the not illustrated switch at the left of switch 14, whose armature 36 occupies in this case the same position as the armature of circuit changer A^2 . In this way the current admitted to trolley wire 17 flows through wire 47 of circuit changer A^1 , wire 57 and contact 55 to bridge 52 where it joins the current supplied thereto from contact 54. Car 72 is thus free to proceed from switch 14 toward switch 15. As soon as the trolley 73 of car 72 leaves wire 21, the current which previously flowed from contacts 54, 55 of circuit changer A^1 through bridge 52, wire 51, windings 48, 49 and wire 50 is interrupted, so that electromagnets 34, 35 become deenergized and their armature 36 is liberated. When trolley 73 engages wire 18 a current will flow from feed wire 28 through branch 25, conduit 60 of circuit changer A^1 , wire 59, winding 58 of electromagnet 32, wire 43 to trolley wire 18, so that electromagnet 32 is energized to attract armature 36 of circuit changer A^1 . Thus a motor circuit is established for car 72, the current flowing through branch 25, armature 36 of circuit changer A^1 , contact 42, wire 41, winding 40 of electromagnet 32, and wire 43 to trolley wire 18. As now the armatures 36 of both circuit changers A^1 and A^2 are swung toward the left, current will be supplied to trolley wire 18 from both of said circuit changers as above described, so that car 72 is free to proceed toward switch 15.

Since car 67 is located closer to switch 15 than car 72, car 67 will reach said switch earlier than car 72. As soon as the car 67 enters with its trolley 74 the trolley wire 22, the current supply to its motor is discontinued, so that it cannot proceed until car 72 has also reached the switch, whereupon current is automatically supplied to trolley wire 22, so that both cars may proceed. It is obvious from Fig. 1 that when car 67 has reached switch 15, while car 72 approaches the latter on track 11, the armature 36 of circuit closer A^2 will remain swung toward the left owing to the current flowing through electromagnet 33 of said circuit changes and through car 72. In this way the bridge 52 of circuit changes A^2 cannot be swung toward contacts 54, 55 so that no current can be supplied to trolley wires 22 and car 67 is thus unable to proceed. As soon as car 72 also enters switch 15, the armature 36 of circuit changer A^2 will be swung toward the right for the following reason: As car 72 leaves the track 11 and trolley wire 18, the flow of current through electromagnet 33 will be interrupted so that both armatures 36 and 38 of circuit changer A^2 are released therefrom. Armature 38

will thus engage contact 66 thereby closing a circuit, the current of which flows from feed wire 28 through branch 26, conductor 60 of circuit changer A², spring 39, armature 38, contact 66, wire 65, winding 64, 63 of electromagnets 35, 34, wire 50, and cars 67, 72 to the track rails. Electromagnets 35, 34 are thus energized to attract armature 36 and thereby throw bridge 52 against contacts 54, 55 of circuit changer A². As in this position of the cars, the armatures 36 of circuit changers A¹, A³ are swung toward the left, current will thus be supplied to trolley wires 22 from both said circuit 15 changers in a manner analogous to that described in connection with switch 14 and car 72 then located in said switch. In addition to thus supplying electric current to trolley wires 22, the trolley wires 21, 23 of 20 the flanking switches are simultaneously cut off from feed wire 28, so that no cars could leave the flanking switches before cars 67, 72 have entered the same. It will be seen that when armature 36 of circuit changer 25 A² is thrown toward the right, two circuits will be established, the currents of which flow through electromagnets 32 and 33 of circuit changers A¹, A³ respectively. As thus the armature 38 of said circuit changers 30 are withdrawn from contacts 66, electromagnets 34, 35 cannot become energized, even if cars should enter the switches, so that the cars are prevented from leaving the same.

35 From the above it will be seen that whenever a car has arrived in a switch and another car is approaching said switch in the opposite direction, the current is automatically cut off from the trolley wires of the 40 switch. The car located in the latter is thus unable to proceed until the other car has also entered the switch, whereupon electric current is supplied to the switch trolley wires, so that both cars are able to proceed. 45 In this way effective means are provided for preventing head-on collisions without the employment of any signal wires between the several track sections, the only wire used being the feed wire for the trolley wire or 50 third rail. For the purpose of the annexed claims, a third rail is obviously to be considered as an equivalent of the trolley wire forming an element of said claims.

I claim:

55 1. In an automatic control system for electric railways, a track composed of a plurality of single track sections and intermediate switches conductively connected thereto, a single trolley wire section for each single track section, a twin trolley wire section for each switch, the wires of each twin trolley wire section being mutually connected and insulated from the adjacent single trolley wire sections, a 60 feeder, and means provided for each switch 65

that are adapted to connect the feeder either with the twin trolley wire sections of said switch or with both of the single trolley wire sections adjacent to said switch.

2. In an automatic control system for 70 electric railways, a track composed of a plurality of single track sections and intermediate switches conductively connected thereto, a single trolley wire section for each single track section, a twin trolley wire section for each switch, the wires of each twin trolley wire section being mutually connected and insulated from the adjacent single trolley wire sections, a feeder, and means controlled by a car-circuit for connecting said feeder to a selected number of trolley wire sections, said controlling car-circuit being established intermediate the switches by means of the connecting single trolley wire sections. 80

3. In an automatic control system for 85 electric railways, a track composed of a plurality of single track sections and intermediate switches conductively connected thereto, a single trolley wire section for each 90 single track section, a twin trolley wire section for each switch, the wires of each twin trolley wire section being mutually connected and insulated from the adjacent single trolley wire sections, a feeder, and circuit changers located in proximity to the switches and controlled by the car-circuits for connecting said feeder to a selected number of trolley wire sections, said circuit 95 changer-controlling car-circuits being established intermediate the switches by means of the respective connecting single trolley wire sections. 100

4. In an automatic control system for 105 electric railways, a track composed of a plurality of single track sections and intermediate switches conductively connected thereto, a single trolley wire section for each single track section, a twin trolley wire section for each switch, the wires of each 110 twin trolley wire section being mutually connected and insulated from the adjacent single trolley wire sections, a feeder, and a circuit changer located in proximity to each switch and controlling connection between the feeder and the trolley wires of said switch and between the feeder and the trolley wire sections adjacent to said switch 115 trolley wires. 120

5. In an automatic control system for electric railways, a single track section and a pair of switches conductively connected to the ends thereof, a single trolley wire for the single track section, a pair of mutually connected trolley wires for each switch, said 125 last named wires being insulated from the single trolley wire, a feed wire, a circuit changer located in proximity to each switch, and means controlled by said circuit changers for connecting the feed wire with the 130

trolley wires of one switch and for simultaneously disconnecting the feed wire from the trolley wires of the other switch.

6. In an automatic control system for electric railways, a single track section and a pair of switches conductively connected to the ends thereof, a single trolley wire for the single track section, a pair of mutually connected trolley wires for each switch, said 10 last named wires being insulated from the single trolley wire, and means controlled by a car for supplying electric current to the trolley wires of one switch and for simultaneously interrupting the supply of electric current to the trolley wires of the other switch.

7. In an automatic control system for electric railways, a single track section and a pair of switches conductively connected to the ends thereof, a single trolley wire for the single track section, a pair of mutually connected trolley wires for each switch, said last named wires being insulated from the single trolley wire, means controlled by a car located in one switch for supplying electric current to the trolley wires of said switch and for simultaneously interrupting the supply of electric current to the trolley wires of the other switch, and means for 25 interrupting the supply of electric current to the twin trolley wires of the first named switch and for supplying electric current to the trolley wires of the single track section when the car passes from said first 30 named switch to said single track section.

8. In an automatic control system for electric railways, a track comprising a pair of single track sections, a central switch intermediate said single track sections and conductively connected thereto, a pair of outer switches conductively connected to the outer ends of said track sections, a single trolley wire section for each single track section, a twin trolley wire section for each of said 40 switches, the wires of each twin trolley wire section being mutually connected and insulated from the single trolley wire sections, and means controlled by a car located in the central switch for supplying electric cur- 45

rent to the trolley wires of said switch and 50 for simultaneously interrupting the supply of electric current to the trolley wires of the flanking switches.

9. In an automatic control system for electric railways, a track comprising a pair of single track sections, a central switch intermediate said single track sections and conductively connected thereto, a pair of outer switches conductively connected to the outer ends of said track sections, a single trolley 60 wire section for each single track section, a twin trolley wire section for each of said switches, the wires of each twin trolley wire section being mutually connected and insulated from the single trolley wire sections, 65 a circuit changer located in proximity to each switch, a feeder, and means controlled by the circuit changers for connecting said feeder to the trolley wires of the central switch and for simultaneously disconnect- 70 ing the feeder from the trolley wires of the flanking switches.

10. In an automatic control system for electric railways, a track comprising a pair of single track sections, a central switch intermediate said single track sections and conductively connected thereto, a pair of outer switches conductively connected to the outer ends of said track sections, a single trolley wire section for each single track 80 section, a twin trolley wire section for each of said switches, the wires of each twin trolley wire section being mutually connected and insulated from the single trolley wire sections, a circuit changer located in 85 proximity to each switch, a feeder, and means controlled by the circuit changers for connecting the feeder to the twin trolley wires of the central switch and for sim- 90 ultaneously disconnecting the feeder from the trolley wires of the flanking switches, said circuit changers being also adapted to connect the feeder with both ends of the trolley wire of each single track section.
